Primary Examiner — Kendra Leslie Hamilton(74) *Attorney, Agent, or Firm* — Ersom IP (Nelson IP)(57) **CLAIM**

The ornamental design for a small lid with straw, as shown and described.

DESCRIPTION

FIG. 1 is a top, front, right perspective view of a small lid with straw, showing our new design closed and in a first configuration;

FIG. 2 is a top, rear, right perspective view thereof;

FIG. 3 is a bottom, front, left perspective view thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof;

FIG. 9 is a bottom plan view thereof;

FIG. 10 is a right side elevation view of the small lid with straw of FIG. 1, shown open and in a second configuration; and,

FIG. 11 is a top, front, right perspective view thereof.

(Continued)

The broken lines depict portions of the small lid with straw that form no part of the claimed design.

1 Claim, 11 Drawing Sheets
